FLUID ACTUATED BELLOWS-TYPE JACK

Robert A. Clay, P.O. Box 1446,
Del Rio, Tex. 78840

Filed June 22, 1973, Ser. No. 372,700

Term of patent 14 years

Int. Cl. D12—05
U.S. Cl. D12—55

FIG. 1 is a front perspective view of a fluid actuated bellows-type jack in expanded position for purposes of illustration;

FIG. 2 is a side view of the fluid actuated bellows-type jack shown in FIG. 1 with the foot stabilizer in folded position; and

FIG. 3 is a back perspective view of the fluid actuated type jack shown in FIG. 1.

The foot stabilizer in FIG. 3 has been shown broken away for convenience of illustration.

I claim:

The ornamental design for the fluid actuated bellows-type jack, as shown and described.
